UNITED STATES PATENT OFFICE

2,306,777

APPARATUS FOR GREASING SHEET
METAL PLATES

Joseph Buzonik, Chicago, Ill.

Application November 4, 1940, Serial No. 364,208

4 Claims. (Cl. 91—51)

The invention relates to an apparatus for greasing sheet metal preparatory to subjecting the material to forming operations.

The practice hitherto followed in the treatment of sheet metal plates consists in taking the plates from an assembled pile and greasing them by hand on both sides, whereupon they are placed in the forming machine to be stamped or punched.

This procedure is cumbersome, expensive and, 10 time-wasting, and therefore obsolete.

It is one of the main objects of the invention to provide an apparatus which eliminates the time wasting and inefficient method of greasing sheet metal plates preparatory to forming the 15 same.

It is a further object of the invention to provide an apparatus in connection with the conveyor mechanism whereby sheet metal plates are placed at one end of the apparatus and subjected to greasing, and thereafter returned to a place not far from the starting end of the apparatus, so that the greased plates may be assembled at a convenient location, eliminating carrying or transportation of the same to the forming machine.

It is also an object of the invention to provide a gravity conveyor in connection with the greasing apparatus so that no motive power is necessary for the conveying of the sheet metal plates.

Other and equally important objects will become apparent from a perusal of the invention, which latter comprises the means described in the following specification, particularly pointed out in the claims, and illustrated in the accompanying drawing, in which:

Fig. 1 is a top plan view of the apparatus constructed in accordance with my invention, and

Fig. 2 is an elevational view with parts shown in section.

Referring to the views of the drawing, 10 designates a truck carrying a pile or stack of sheet metal plates 11. A roller conveyor, generally designated by 12, comprises longitudinal members 13 and 14, in which plurality of parallel spaced rollers 15 are journaled.

The conveyor 12 is inclined downwardly from its point of origin and is supported at its lowermost end on a tank 16 in which oil is contained.

A transverse roller 17 is journaled in the end walls 18 of the tank and cooperates with the superposed transverse roller 19 whose shaft 20 is journaled at one side in a bearing 21 and

projects at the other end through a slot 22 in which a spring 23 maintains the roller 19 in resilient engagement with the roller 17.

The shaft 24 of the roller 17 and the shaft 20 are provided in the mating gears 25, whereby rotation from the roller 19 is imparted to the roller 17.

The shaft 20 is provided with a pulley 26 around which a belt 28 is trained, encompassing a pulley 27 on the shaft of a motor 29, which is energized from a suitable source of electrical energy, not shown, which causes rotation of the roller 19 which, in turn, rotates the roller 17.

A speed reducer 30 is interposed between the motor and the pulley 28 so as to impart proper speed of rotation to the roller 19.

A spray pipe 31 extends alongside of the upper roller 19 for emission of oil, and leads to a pump 32 adapted to pump oil from the tank 16 to the spray pipe.

A pulley 33 is in alignment with the pulley 34 on the shaft 20 and a belt 35 is trained around the aligning pulleys 33 and 34.

The tank is provided with a drain pipe 36 for the purpose of draining the oil when necessary to change the same.

A roller conveyor 37 is supported at one end on the tank 16 and, from then on, is inclined downwardly to constitute a gravity conveyor.

The conveyor 37 continues into a semi-circle 38, and thence continues parallel to the conveyor 12, and leads to a tank 39, whereto the sheet metal plates are delivered for deposit.

The tank 39 is provided with a drain pipe 40 to enable the reclaiming of the oil dripping from the plates for return to the tank 16 by a pipe connection (not shown).

It is evident that, by reason of the U-shaped form of the conveyor 37, the tank 39 may be arranged proximate to a forming machine 41, diagrammatically indicated in Fig. 1, so that an operator may conveniently remove the greased plates from the tank 39 and place them in the forming machine for further treatment.

It is evident that the apparatus eliminates unnecessary steps in greasing the plates, which is carried out automatically once the plates are placed on the conveyor 12, and the greased plates are then brought back to the operator by conveyor 37 to a position proximate to the forming machine, for convenient handling of the greased plates.

While the drawing shows one embodiment of the invention, numerous changes and alterations

may be made without departing from the spirit of the invention.

I, therefore, do not limit myself to the particular arrangements of parts nor the construction as shown by way of example, but wish to include all changes, modifications, variations and revisions constituting departures within the scope of the invention, as defined in the appended claims.

I claim:

1. Apparatus for greasing sheet metal plates, including a pair of greasing rollers, a tank containing oil in which one of said rollers is partly immersed, a conveyor carrying the plates past said rollers, and a U-shaped conveyor for transporting the greased plates to a point proximate to the starting location to be arranged in stack formation.

2. Apparatus for greasing sheet metal plates, including a pair of greasing rollers, a conveyor carrying the plates past said rollers, a discharge

10 tank proximate to the starting point of said conveyor, and means for conveying the plates from said rollers to said tank to be arranged in stack formation.

5 3. Apparatus for greasing sheet metal plates, including a pair of greasing rollers, a gravity conveyor carrying the plates past said rollers, a discharge tank proximate to the starting point of said conveyor, and gravity means for conveying the plates from said rollers to said tank to be arranged in stack formation.

15 4. Apparatus for greasing sheet metal plates, including a pair of greasing rollers, a gravity conveyor carrying the plates past said rollers, a discharge tank proximate to the starting point of said conveyor, gravity means for conveying the plates from said rollers to said tank, and means for collecting the oil accumulating in said discharge tank.

JOSEPH BUZONIK.
